W. G. ROBINSON

WIRE FENCE CLAMP

Filed Dec. 21, 1922

UNITED STATES PATENT OFFICE.

WILLIAM G. ROBINSON, OF BATAVIA, IOWA.

WIRE-FENCE CLAMP.

Application filed December 21, 1922. Serial No. 608,296.

To all whom it may concern:

Be it known that I, WILLIAM G. ROBINSON, a citizen of the United States, residing at Batavia, in the county of Jefferson and State of Iowa, have invented certain new and useful Improvements in Wire-Fence Clamps, of which the following is a specification.

My invention relates to clamping devices especially adapted for use upon wire fence fabrics, when stretching the same, and one object of the invention is to provide such a clamp, which is of simple and durable construction, and which may be easily and quickly applied to the fence fabric and as easily detached therefrom.

One embodiment of the invention is illustrated in the accompanying drawing, wherein—

20 Figure 1 shows a side elevation of the device in operation;

Figure 2, a top plan view of Figure 1, and Figure 3, a fragmentary end view of Figure 1.

25 In the drawing, reference numeral 10 represents a wire net of any kind suitable for fence construction, and clamps, indicated, in general, by numeral 11, gripping the wire in order to stretch the same preparatory to 30 fastening it to a fence post.

Each clamp consists of two jaw members 12 and 13 of L-shape, the long arm of which terminates with an ear 14, to which a link 15 is attached to swivel around a pin or 35 rivet 16.

The short arms 17 and 18 of the jaw members 12 and 13 are turned inwardly approximately 90 degrees from the long arms thereof. One of these short arms terminates with 40 a hook 19 and the other short arm 18 terminates with a corresponding eyelet 20 adapted to interengage. The flat, opposing surfaces 21 of the short arms 17 and 18 are spaced apart, as best seen in Figure 2, and in this 45 space is inserted the long legs 22 of the angle irons 23, while the other legs 24 thereof reach across to the long arms of the jaws 12 and 13. The angle irons 23 are of sufficient length to accommodate two each of these 50 jaws 12 or 13, as seen in Figure 1, and flanges or wings 25, running up and down from the jaws, furnish securing means for the angle irons 23, which are held in position by rivets 26 or the like.

55 In this manner two pairs of jaws are furnished, one situated above the other on one

pair of angle irons 23, best seen in Figure 1 of the drawing. The links 15 are connected by means of a hook 27, to which is attached a cable or chain 28 for pulling the jaws in 60 the direction of arrow X, in order to stretch the wire fabric.

The operation of the device is as follows:

The two pairs of jaws are separated, together with their angle irons 23, that is to say, the connection 19 and 20 is unhooked and the wire net is then entered between the angle irons 23, and the hooks and eyes 19 and 20 coupled together a short distance back of the end of the wire net, as seen in Figures 1 and 2 of the drawings. The long arms of the jaws 12 and 13 are then drawn together until the legs 22 of the angle irons 23 close up around the wire net, so as to hold it firmly and in flat position, whereupon the hook 27 is introduced into the links 15. By now exerting a pull upon the cable or chain 28, the wire net will be stretched in the direction of arrow X, it being assumed that the opposite end of the wire net is secured 70 on a fence post.

After the end of the wire net, where the clamps are attached, has been secured to the fence post at this end, the pull on the cable or chain 28 is slackened, whereupon the 75 clamps will release their hold upon the wire net and may then be readily removed therefrom by swinging the long arms of the jaws 12 and 13 apart sufficiently to permit the disengagement of the hooks and eyelets 19 and 20, whereupon the operation is repeated at 80 the next fence post.

By making the jaws 12 and 13 in L-shape with the short arms 17 and 18 offset in inward direction, a very simple construction 95 has been provided and it will be evident that no other operation is needed beyond the drilling of the holes for the rivets 26 in the angle irons 23 for securing the latter to the jaws. Another advantage of constructing 100 the clamps in this manner resides in the fact that the angle irons do not need to be weakened in any manner to carry the jaws 12 and 13.

Another advantage of the construction of 105 this device is that, no machining whatsoever is required as the parts may be forged or cast in this shape, and that, the necessary apertures for the rivets and pins may be cored.

110 The advantage of using angle irons for gripping the wire net will readily be under-

stood as the wires, in this manner, are held in flat position between the angle irons and, accordingly, no crimping or bending of the wires will occur as is the case of other devices of similar character.

Having thus described the invention, what is claimed as new is:

1. A fence clamp comprising a pair of jaws detachably interlocked at one end thereof, flat-faced wings integral with the jaws, angle bars secured on said wings, and means for drawing the free ends of the jaws together.

2. A fence clamp comprising a pair of angle bars constituting gripping members, mating jaw members having each a long and a short arm, said short arms having interlocking elements, wings integral with said jaw members positioned at the juncture of said long and short arms, said wings being rigidly united with the respective angle bars, and means for drawing said long arms together.

In testimony whereof I affix my signature.

WILLIAM G. ROBINSON. [L. S.]
